UNITED STATES PATENT OFFICE.

CHARLES W. HOWELL, OF NEWARK, NEW JERSEY, ASSIGNOR TO UNDERWOOD ELLIOTT FISHER COMPANY, OF NEW YORK, N. Y., A CORPORATION OF DELAWARE.

TYPEWRITING MACHINE.

Application filed December 2, 1927. Serial No. 237,175.

This invention relates to the adjustment of the platen in case-shift typewriting machines of the portable type, in which a case-shift frame is mounted in the main frame 5 of the typewriting machine by means of parallel link systems at the sides of the machine.

As the type-bars of the machine are usually arranged to strike an abutment on the type-bar-segment upon which they are 10 mounted when the type-faces are in typing position at the typing plane, it is essential to maintain a proper relation of the typing line of the platen with respect to this typing plane. This invention deals with adjustments 15 for correcting the position of the platen to true it up.

According to the present invention the adjustments are made by increasing or decreasing the length of one of the parts at each 20 side of the typewriting machine in order to shift the ends of the platen forwardly or rearwardly as may be required, to bring the printing line on the platen into the proper printing plane. Heretofore, the adjustments 25 have been accomplished by means of changes in the pivotal articulation between the case-shift-frame and the main frame by changing or shifting one or more of the pivotal connections. In the present invention 30 the adjustment is accomplished by varying the distances between parts, and is shown applied to the upper link of the parallel link- 35 system at each side of the case-shift-frame, whereby the length of the link may be increased or diminished for making the adjustment. The link is provided with a projection 40 midway between its ends, and is separated into two sections by means of an interrupting slot which extends across the link and into the projection. The portion of the 45 projection beyond the slot provides a resilient flexing connection between the sections of the link, and the adjustment of the link is maintained by means of a screw-connection between the two sections across the slot, which screw-connection affords a means for 50 obtaining a very fine adjustment to correct very slight variations in length of the link necessary to bring the printing line of the platen into the proper printing plane.

A feature of the invention is the accessibility of the adjustments; the adjusting devices on the upper link of the parallel link-system extend outwardly into a recess in the 55 main frame of the typewriting machine

where they can be readily operated upon. The adjusting devices are extremely compact, simple and inexpensive to apply during the manufacturing of typewriting machines.

Other features and advantages will hereinafter appear.

In the accompanying drawings,

Figure 1 is a sectional side elevation of the right-hand side of the typewriter, showing the parts employed in the case-shift operation and platen-adjusting devices, in accordance with the present invention, applied thereto.

Figure 2 is a perspective view, showing the relation between the stationary frame and shift-frame of an Underwood portable typewriter and the link-connection between said frames having the adjusting devices applied thereto. Portions of the platen and type-bar-segment and a type-bar are shown in their relative position with respect to the frames.

Figure 3 is a perspective view of one of the guide-link connections to which the platen-adjusting device, according to this invention, has been applied.

The typewriting machine herein illustrated includes a main frame 10 and a shift-frame 11 carrying a reciprocating platen-carriage 12, in which a platen 13 is rotatably mounted. The machine is provided with the usual type-bar-segment 14, and one of the type-bars 15 carried thereby is shown in typing position, the bar resting against the usual type-bar-segment abutment 16 and type-head 17 on the end of said type-bar against the platen, the platen being illustrated in lower-case typing position.

The platen-carriage 12 is provided with guide-rails 18 and corresponding front and rear guide-rails 19 and 20, respectively, are mounted on the shift-frame 11. Rails 18 of the platen-carriage co-operate with ball-bearings 21 and the front and rear-guide rails 19 and 20 on the shift-frame to permit the platen-carriage to reciprocate with respect to the shift-frame in the usual manner. The usual means for actuating the platen-carriage upon the shift-frame for letter-spacing is indicated by a rack 22 provided on the carriage and which is associated with a pinion 23, escapement 24 and spring-drum 25 provided on the shift-frame structure.

The shift-frame 11 includes a rear plate 110

26 and side plates 27, which carry the respective rear and front rails 20 and 19 on the upper portions thereof. The side plates extend forwardly, and on the upper portion of 5 the outer ends thereof are formed ears 28 for carrying ribbon-mechanism (not shown).

The shift-frame 11 is operated within the main frame 10 for up-and-down case-shift movement in a plane substantially parallel to 10 the printing plane of the type-bars. This movement is obtained by means of parallel link-connections between the shift-frame and the main frame, including an upper guide-link 29 and a lower guide-link 30 at either 15 side of the machine. The rear ends 31 and 32 of the upper and lower guide-links, respectively, are pivotally connected to the main frame and the forward ends 33 and 34, correspondingly, to the side plates 27 of the 20 shift-frame. The lower guide-links 30 are forwardly connected to the shift-frame by means of pivots 35 and are rearwardly secured upon a rocker-shaft 36, which is detachably journaled in the main frame by 25 means of screws 37, and which, as will be seen, effects a simultaneous movement of the two lower guide-links 30 during case-shift movement of the shift-frame effected at either side of the machine.

30 As shown in Figure 1, a right-hand case-shift lever 38 is pivotally connected at 39 to the main frame. The rearward arm 40 of said lever co-operates with an inward extension of the pivot 35 of the right-hand 35 lower guide-link 30. Upon depressing a key 38^a, mounted on the forward arm 41 of the lever, the rearward arm 40 thereof will operatively engage said pivot 35 to lift the shift-frame to its upper-case position. To limit 40 the case-shift movement, an extension 42 of said right-hand lower guide-link 30 operates between a lower stop-screw 43 and an upper stop-screw 44. Said stop-screws 43 and 44 are adjustably threaded into ears 45 45 (see Figure 2) extending from the main frame, and are locked in place by lock-nuts 46. The shift-frame is shown in lower-case position with the extension 42 resting upon the lower stop-screw 43. The case-shift lever 50 50 is normally held by a spring 47, so that a projection 48 on the rear arm 40 of the lever is held in engagement with an edge 49 of an opening 50 in the main frame.

The shift-frame 11 is guided between the 55 heads of screws 51 which pass through the pivotal points at the ends 31 of the upper guide-links 29 at either side of the shift-frame and are secured in the main frame, as shown in Figure 2. The heads of screws 51 60 extend sufficiently to engage the shift-frame 11 as lateral stops to prevent sidewise play of the shift-frame with respect to the main frame of the typewriting machine.

In order to adjust the platen so that the 65 printing line thereof will be in the correct

plane at both ends thereof, adjusting devices, generally designated by the numeral 52, are provided so that the ends of the platen and the shift-frame 11 may be moved forwardly or rearwardly with respect to the 70 main frame 10 of the typewriting machine. The normal position of the shift-frame and parts carried thereby is indicated in full lines with the type-heads 17 in proper printing position with respect to the platen, and forward and rearward adjusted positions of the typing section of the platen and the corresponding positions of the forward portion of side plates 27 are indicated in dot-and-dash lines in Figure 1. The adjusting devices provide for the rocking of the shift-frame 11 on the pivots 35, so as to correctly position the guide-rails 19 and 20, and in order that the reciprocating platen-carriage and parts moving therewith may be correctly positioned to bring the printing line of the platen into the proper printing plane of both lower and upper case-shifts, each end of the platen is independently adjusted. The 80 adjusting devices 52 are applied to the upper guide-links 29 and the pivotal connections of both the upper and lower guide-links with the main frame 10 and the shift-frame 11 are unaltered.

In order to make the upper guide-links 29 90 adjustable, each link is provided at its middle portion with a downward projection 53 and a slot 54 extending from the upper surface of the link down into said projection 53, so that the portion 53^a at the bottom of the slot will provide a flexible connection between the two ends of the link whereby the length of the link may be increased or diminished. As best shown in the detailed view of the link (Figure 3), outwardly-extending ears 55 and 56 100 are fastened to the link on either side of the slot 54 adjacent to the upper portion thereof. The link may be formed with a shoulder 53^b, to increase its lateral dimension at the point where the ear 56 is attached, whereby 110 no flexing will occur at this point to vary the adjustment of the platen-carriage. The ear 55 is provided with a hole 57 of sufficient size to permit the shank of a screw 58 to pass freely therethrough, and the ear 56 is provided with a threaded hole 59 into which said screw 58 is threadably received. Two lock-nuts 60 and 61 are provided for the screw 58 to engage the ears 55 and 56, respectively. These nuts securely hold the screw 58 in place by 120 gripping against the ears 55 and 56 and thereby maintain the adjustment of the length of the guide-link 29.

The main frame 10 is formed with recesses 62, at each side thereof, into which recesses 125 the laterally-projecting portions of the adjusting device freely extend and in which position they are within easy access for manipulation in the process of adjusting the platen.

In order to adjust the platen, the lock-nuts 130

60 and 61 are loosened to permit the screws 58 to be turned in or out for either shortening or lengthening the guide-links 29. The screws may be turned inwardly for drawing 5 the ears together, to shorten the guide-links and thereby swing the shift-frame forwardly on the pivot 35 to bring the face of the platen forwardly with respect to the printing plane. Likewise, the screws may be turned outwardly 10 to allow for lengthening of the guide-links for swinging the platen rearwardly with respect to the printing plane. After the screws are adjusted, the lock-nuts are tightened to fasten the parts in proper relation 15 with nuts 61 against the ears 56, to lock the screws from turning, and nut 69 against ears 55 to hold these ears against movement on the screws. In some instances, when the screws have been turned out, the nuts may force the 20 ears outwardly to lengthen the guide-links, but, preferably, the guide-links are formed so that they will extend, due to their resiliency, sufficiently to take care of the maximum adjustments in either direction. As it is necessary 25 that the adjustment of the platen be made very accurately in order to obtain clearness and evenness of the individual type-impressions and of the impressions from one end of the platen to the other, the adjustments at each end of the platen are made independently. In each guide-link, it will be noted that the screw 58 provides a micrometer adjustment for varying its length, whereby very slight variations in the length of the guide-link 30 may be readily obtained, and the adjustment thereof is greatly facilitated.

Variations may be resorted to within the scope of the invention, and portions of the improvements may be used without others.

Having thus described my invention, I 40 claim:

1. A typewriting machine including, in combination, a main frame, a shift-frame upon which a platen-carriage and a platen are reciprocably mounted, pivotally-mounted type-bars carrying type-heads for typing in different case-shift-positions, means for limiting the swinging movement of the type-bars towards the platen to determine the printing 45 points of the type-heads, swingable guide-links at each side of said shift-frame connecting the shift-frame within the main frame to move up and down therein for typing in the different case-shift positions, and means for varying the length of a guide-link at each side 50 of the shift-frame independently, so as to adjust the printing line of the platen forwardly or rearwardly with respect to the printing points of the type-heads to obtain clearness 55 and evenness of type-impressions from one end of the platen to the other.

2. A typewriting machine including, in combination, a main frame, a shift-frame within said main frame upon which a platen-carriage and a platen are reciprocably mount- 60

ed, swinging type-bars, a pair of guide-links at either side of said shift-frame for connecting it with the main frame and guiding it during case-shift-movements, and means for varying the length of one of the guide-links 70 at each side of said shift-frame to obtain the proper relation between the platen and type-bars for clear and even type-impressions from one end of the platen to the other.

3. A typewriting machine including, in combination, a main frame, a shift-frame upon which a platen-carriage and a platen are reciprocably mounted, swinging type-bars, a pair of guide-links at either side of said shift-frame for connecting it within the main frame and guiding it during case-shift-movements, including upper and lower horizontally-arranged links with the upper one at each side in an accessible position adjacent to the upper portions of the frames, and means for varying the length of said upper guide-links independently of each other to obtain the proper relation between the platen and type-bars for clear and even type-impressions from 80 one end of the platen to the other. 90

4. A typewriting machine including, in combination, a main frame, a shift-frame consisting of a back-member and forwardly-extending side members, rails mounted over said back-member and the rear portion of 95 said side members of the shift-frame, a platen-carriage reciprocably mounted on said rails, a platen in said carriage, swinging type-bars, means for mounting said shift-frame in said main frame including horizontally-arranged guide-links at each side of the shift-frame pivotally connected at their rear ends with said main frame and at their front ends in front of said rails with the forward portions of the side members of said shift-frame, 100 means at each side of the machine for adjusting said rails forwardly and rearwardly with respect to the main frame including a longitudinally-adjustable connection in one of the aforesaid parts at each side of the machine, 105 and means for holding said connections in adjusted positions for positioning the typing line of the platen in proper relation with respect to the type-bars for obtaining clear 110 and even impressions from one end of the 115 platen to the other.

5. A typewriting machine including, in combination, a main frame, a shift-frame within said main frame upon which a platen-carriage and a platen are reciprocably mounted, swinging type-bars, a pair of guide-links at either side of said shift-frame for connecting it with the main frame and guiding it during case-shift-movements, one of said links at each side of the shift-frame being formed in two sections having a flexible connection between them, whereby the length of the link may be varied, and means for securing said sections of the link at each side 120 of the shift-frame to an adjusted length for 125 130

positioning the typing line of the platen in proper relation with respect to the type-bars for obtaining clear and even impressions from one end of the platen to the other.

- 5 6. A typewriting machine including, in combination, a main frame, a shift-frame within said main frame upon which a platen-carriage and a platen are reciprocably mounted, swinging type-bars, a pair of guide-links
10 at either side of said shift-frame for connecting it with the main frame and guiding it during case-shift-movements, one of said links at each side of the shift-frame being formed in two sections having a flexible connection
15 between them, whereby the length of the link may be varied, apertured ears extending laterally from the adjacent ends of the link-sections, and a screw passing through the apertures in said ears and in engagement therewith for securing the sections of the link at each side of the shift-frame to an adjusted length for positioning the typing line of the platen in proper relation with respect to the type-bars for obtaining clear and even impressions
20 from one end of the platen to the other.

7. A typewriting machine including, in combination, a main frame, a shift-frame within said main frame upon which a platen-carriage and a platen are reciprocably mounted, swinging type-bars, a pair of guide-links at either side of said shift-frame for connecting it with the main frame and guiding it during case-shift movements, one of the
30

links at each side of the shift-frame being formed with a lateral projection and having a slot extending through the link and into said lateral projection dividing the link into two sections having a flexible connection between them, whereby the length of the link may be varied, apertured ears extending laterally from the ends of the link-sections adjacent to said lateral projection, and a screw passing through the apertures in said ears and in engagement therewith for securing the sections of the link at each side of the shift-frame to an adjusted length for positioning the typing line of the platen in proper relation with respect to the type-bars for obtaining clear and even impressions
40
45 from one end of the platen to the other.

8. A typewriting machine including, in combination, a main frame, a case-shift-frame within said main frame upon which a platen-carriage and a platen are reciprocably mounted, and a parallel link-system at each side of said case-shift-frame for connecting it with the main frame, whereby the typing line of the platen is shiftable substantially in a plane, one of said links at each side of the case-shift-frame being of adjustable length, whereby the case-shift-frame may be shifted to adjust the platen forwardly or rearwardly until the typing line of the platen is in the proper printing plane, said links being independently adjustable.

CHARLES W. HOWELL.
